UNITED STATES PATENT OFFICE.

GEORGE W. WAREHAM, OF PITTSBURG, PENNSYLVANIA.

MATTRESS-FILLER.

SPECIFICATION forming part of Letters Patent No. 717,955, dated January 6, 1903.

Application filed July 19, 1902. Serial No. 116,215. (No model.)

To all whom it may concern:

Be it known that I, GEORGE W. WAREHAM, of Pittsburg, in the county of Allegheny and State of Pennsylvania, have invented certain new and useful Improvements in Mattress-Fillers; and I do hereby declare the following to be a full, clear, and exact description of the invention, such as will enable others skilled in the art to which it appertains to make and use the same.

This invention relates to certain new and useful improvements in mattress-filters.

The invention has for its object the production of a simple and efficient mattress-filler which may be regulated to fill mattresses of different widths.

A further object is to provide an improved feed-roller and end gate which can be readily adjusted to the various widths of the mattress-filler, and thus avoid the substitution of new parts after each adjustment.

A further object is to provide tick-guides which may be adjusted for mattresses of varying thicknesses.

In carrying out my invention I provide a suitable frame or support on which are mounted two removing-sheets the edges of which overlap, suitable means being provided for varying the relative positions of said removing-sheets. At the forward end of the machine is pivotally mounted an end gate made up of two telescoping sections, the relative positions of which are regulated simultaneously with the regulation of the varying positions of said removing-sheets. The sections of said end gate are mounted in bearing-bars pivotally supported by the side bars of the frame, said bearing-bars also serving to support the shaft of a feed-roll when the latter

is in its operative position. Said feed-roll is also formed of telescoping members, whereby said roll may be adjusted to conform to the relative positions of the removing-sheets. The tick-guides are secured to the side bars and are each formed of two sections, means being provided for adjusting said sections vertically to conform to ticks of different thicknesses.

The invention will be hereinafter fully set forth, and particularly pointed out in the claims.

In the accompanying drawings, Figure 1 is

a transverse section of my improved mattress-filler. Fig. 2 is a detail side elevation illustrating the feed-roll and its adjuncts. 55 Figs. 3 and 4 are detail views of the end gate and tick-guides, respectively. Fig. 5 is a detail illustrating the device for effecting the adjustment of the removing-sheets.

Referring to the drawings, 10 designates a 60 frame or support in which are mounted the sliding removing-sheets 11 12, the former overlapping the latter, as indicated at 13. The removing-sheet 11 is moved back and forth by means of a sprocket-chain 14 passing over 65 wheels 15 and connected to a bar 16, which is arranged to automatically engage and be disengaged from the side bar 17 of said removing-sheet by means of an angle-plate *a*, having a perforation arranged to receive a pin or lug *b* carried by the end bar *c* of said removing-sheet. In practice the relative positions of the removing-sheets are regulated by means of the chain 14 to suit the different widths of ticks to be filled. 75

In the forward ends of the side bars of the frame 10 are pivotally mounted bearing-bars 18, said bearing-bars being provided at their forward ends with inwardly-extended studs or pins 19, arranged to enter the tubular portions 20 of an end gate 21, whereby the latter is pivotally supported. Said end gate is formed of two telescoping members 22 23, the former being stationary and the latter adjustable simultaneously with the side bar 17. 80 85 The bearing-bars 18 are raised and lowered by means of hand-levers 24, keyed to the pivots 25, said levers having each an arm or extension 26, connected by a link 27 to a rock-shaft 28, whereby said levers will move in unison.

The feed-roller 29 comprises two sections 30 31, the shell 32 of the former being secured around spiders 33, keyed to a shaft 34, said shaft being rotatably supported by bearing-bars 35, which are pivotally mounted in arms or supports 36, carried by the frame or support 10. The shell 37 of the section 31 overlaps section 30 at one end, the other end thereof being secured to a spider 38, having a key 90 or spline 39, fitting in a keyway or groove 40, whereby said section may be moved back and forth. On each end of shaft 34 are keyed sprocket-wheels 41, connected by chains 42

with wheels 43, keyed to the pivot or rock shaft 44 of bearing-bars 35. Sprocket 45 is also keyed to shaft 44 and connected by a chain 46 to a sprocket 47, keyed to a short shaft 48, mounted in the frame or support 10. Said shaft is rotated by means of a pinion 49, meshing with a corresponding pinion 50, keyed on one end of shaft 51. Said shaft is rotated by means of sprockets 52, which are engaged by chains 53, operated from any suitable source of power. Said chains 53 engage and feed the removing-sheets forward into the tick and withdraw the same after said tick is filled. The feed-roll is moved into and out of operative position by means of a lever *d*, pivoted to the frame 10 and having an arm or pitman engaging one of the bearing-bars 35.

The tick-guides are each made of a lower stationary section 54 and an upper adjustable section 55. The latter is provided with a block or extension 56, having a threaded hole or opening arranged to receive a threaded adjusting-shaft 57, the lower end of which is loosely mounted in a block 58, carried by the side bars. The block 56 is provided with a depending rod or guide 59, arranged to slide in a hole or opening 60 in block 58.

In practice when it is desired to fill a tick the desired width is obtained by the adjustment of the removing-sheets through the medium of chain 14. It will be particularly noted in this connection that the adjustment of the removing-sheets just referred to will simultaneously effect a corresponding adjustment of the sections of the feed-roll and the end gate and also of the relative position of the tick-guides. The members of the tick-guides are then adjusted relatively to each other to accommodate the desired thickness of the mattress to be made. The filling material is then distributed on the removing-sheets, after which the end gate is raised and the feed-roller moved to its operative position. The chains 53 are then started in operation, feeding the removing-sheets into the tick, which is supported by the tick-guides, the feed-roll being rotated simultaneously therewith and effecting an even feed of the filling material.

The advantages of my improved mattress-filler will be at once apparent to those skilled in the art to which it appertains. It will be particularly observed that the removing-sheets, feed-roll, and end gate are readily capable of simultaneous and conjoint adjustment to fit mattresses of different widths and that by means of my adjustable tick-guides mattresses of different thicknesses may be filled, all of said adjustments being readily accomplished with but a minimum expenditure of time and labor.

I claim as my invention—

1. A mattress-filler comprising a frame or support, removing-sheets carried thereby, means for feeding said removing-sheets forward, a swinging end gate, and means

for simultaneously adjusting said removing-sheets and end gate for mattresses of different widths, as set forth. 70

2. A mattress-filler comprising a frame or support, removing-sheets carried thereby, an extensible feed-roller, and means for simultaneously adjusting said removing-sheets and feed-roller for mattresses of different widths, 75 as set forth.

3. A mattress-filler comprising a frame or support, removing-sheets carried thereby, an extensible feed-roller, an end gate, and means for simultaneously adjusting said removing-sheets, feed-roller and end gate for mattresses of different widths, as set forth. 80

4. A mattress-filler comprising a frame or support, overlapping removing-sheets carried thereby, an end gate formed of two telescoping swinging members, and means for simultaneously adjusting said removing-sheets and end gate to mattresses of different widths, as set forth. 85

5. A mattress-filler comprising a frame or support, overlapping removing-sheets carried thereby, bearing-bars carried by said frame or support, an end gate formed of telescoping sections and mounted to swing between said bearing-bars, and means for simultaneously 95 adjusting said removing-sheets and said end gate for mattresses of different widths, as set forth.

6. A mattress-filler comprising a frame or support, overlapping removing-sheets carried 100 thereby, bearing-bars carried by said frame or support and carrying studs, an end gate formed of telescoping sections and provided with tubular portions fitting over said studs, and means for simultaneously adjusting said 105 removing-sheets and said end gate for mattresses of different widths, as set forth.

7. A mattress-filler comprising a frame or support, overlapping removing-sheets carried thereby, pivoted bearing-bars, means for 110 elevating the same, an end gate formed in telescoping sections and mounted to swing between said bearing-bars, and means for simultaneously adjusting said removing-sheets and said end gate for mattresses of different 115 widths, as set forth.

8. A mattress-filler comprising a frame or support, overlapping removing-sheets carried thereby, pivoted bearing-bars, hand-levers connected thereto, a rock-shaft, connections between said shaft and said hand-levers, an end gate formed of telescoping sections mounted to swing between said bearing-bars, and means for simultaneously adjusting said removing-sheets and said end gate for mattresses of different 125 widths, as set forth.

9. A mattress-filler comprising a frame or support, overlapping removing-sheets carried thereby, a feed-roll formed of two telescoping sections, and means for simultaneously adjusting said removing-sheets and said feed-roll to mattresses of different widths, as set forth. 130

10. A mattress-filler comprising a frame or

support, overlapping removing-sheets carried thereby, bearing-bars carried by said frame or support, a shaft mounted in said bearing-bars, a feed-roll mounted on said shaft and formed in two telescoping sections, and means for simultaneously adjusting said removing-sheets and said feed-roll to mattresses of different widths, as set forth.

11. A mattress-filler comprising a frame or support, overlapping removing-sheets carried thereby, bearing-bars carried by said frame, a shaft mounted in said bearing-bars, a feed-roll mounted on said shaft and formed of two telescoping sections, an operating-lever connected to said bearing-bars, and means for simultaneously adjusting said removing-sheets and said feed-roll for mattresses of different widths, as set forth.

12. A mattress-filler comprising a frame or support, overlapping removing-sheets carried thereby, a shaft supported by said frame or support, spiders rigidly keyed thereon, a casing surrounding said spiders, a spider mounted to slide on said shaft, a casing secured thereto and telescoping with said former casing, and means for simultaneously adjusting said removing-sheets and changing the relative position of said sliding spider, as set forth.

13. A mattress-filler comprising a frame or support, overlapping removing-sheets carried thereby, a feed-roll formed of two telescoping sections, means for simultaneously adjusting said removing-sheets and said feed-roll for mattresses of different widths, and means for simultaneously feeding said removing-sheets and rotating said feed-roll, as set forth.

14. A mattress-filler comprising a frame or

support, overlapping removing-sheets carried thereby, a feed-roller formed in sections, an end gate also formed in sections, tick-guides carried by said frame or support, and means for simultaneously adjusting said removing-sheets, feed-roll, end gate and tick-guides for mattresses of different widths, as set forth.

15. A mattress-filler comprising a frame or support, tick-guides carried thereby and provided with adjustable members, means for adjusting said members, and depending guide-rods carried by said adjustable members, as set forth.

16. A mattress-filler comprising a frame or support, stationary and adjustable supporting members mounted on said frame, tick-guides carried by said supporting members, means for adjusting said adjustable members, and depending guide-rods carried by said latter members and engaging said stationary members, as set forth.

17. A mattress-filler comprising a frame or support, tick-guides carried thereby, said tick-guides being formed of stationary and movable sections, blocks carried by said frame, threaded rods mounted in said blocks, blocks carried by said movable sections and engaging said rods, and depending guide-rods carried by said latter blocks and passing through said former blocks, as set forth.

In testimony whereof I have signed this specification in the presence of two subscribing witnesses.
